UNITED STATES PATENT OFFICE.

SWAN LARSON, OF ROCKFORD, ILLINOIS, ASSIGNOR TO GEO. D. ROPER CORPORATION, OF ROCKFORD, ILLINOIS, A CORPORATION OF ILLINOIS.

PUMP.

Application filed April 20, 1925. Serial No. 24,345.

My invention relates to pumps of the reciprocating type and more especially to hand and wind mill force pumps adapted to be interchangeably employed a lift pump, and 5 the invention consists in certain novel combinations and arrangements of parts as will be more fully described.

Heretofore, it has been customary to construct the cap or supporting bracket upon 10 which the handle and fulcrum are pivoted, as a single casting having a longitudinal slot or central opening to receive the handle or operating lever and to provide guide means for the pump rod, including the upper slide bar and the piston rod, at the upper and lower ends of said cap. The manufacture of the cap in a one-piece casting as above expressed required coring, an expensive operation in view of the peculiar formation 15 of the cap and the large opening required to accommodate the moving parts. Furthermore, it was not possible readily to adapt the pump for use as a compression or force pump and as a lift pump.

20 The present invention overcomes the above objections and among the objects thereof are to provide a pump having a novel adjustable stroke cap or bracket on which the pump handle is fulcrumed and 25 which serves as a guide for the slide bar and piston rod; novel means for adjusting the stroke of the piston and operation either as a hand pump or a wind mill pump; to so construct the cap in two parts that coring is 30 eliminated and manufacture and assembling facilitated thereby providing for quantity production and reducing the cost; to provide novel means for adjusting the position and points of connection of the fulcrum with 35 the handle and cap, and the fulcrum for the handle shifter whereby the stroke of the piston may be adjusted without disassembling the parts or dismantling the cap and operating handle or lever, and to provide novel top 40 bearing plates secured to the pump base jointly with the cap and guide means for the pump rod.

45 Other objects and attendant advantages will be appreciated by those skilled in this art as the invention becomes better understood by reference to the following description when considered in connection with the accompanying drawings, in which—

Figure 1 is a side elevation of a pump

constructed in accordance with my invention and showing the same in use as a force or compression pump.

55 Fig. 2 is an enlarged front elevation showing the upper part of the pump and the operating parts to which the invention especially relates.

Fig. 3 is an enlarged vertical sectional elevation of the structure shown in Fig. 2.

Fig. 4 is a horizontal sectional view taken 60 on the line 4—4 of Fig. 3.

Fig. 5 is a horizontal sectional view taken 65 on the line 5—5 of Fig. 3.

Fig. 6 is a vertical sectional view taken 70 on the line 6—6 of Fig. 1, and

Fig. 7 is a fragmentary sectional view 75 showing the adaptation of the pump as a lift pump.

Referring to the drawings in detail where- 80 in I have illustrated an embodiment of the invention and in which similar reference characters designate corresponding parts throughout, 8 designates the base of the pump which may be suitably braced, 9 the spout and 10 the upper portion of the base arranged to form an air chamber or dome 85 for use in connection with a compression or force pump. The part 10 has a reduced neck portion 11 formed with an outwardly extending annular flange 12 at the top enlarged internally as indicated at 13 and having an upstanding bearing surface or shoulder 14 adapted to receive a packing ring or gasket 15 of heavy tar paper or other suitable material. By this construction a narrow annular packing surface is provided, 90 thereby requiring less finishing than if the entire annular flange 12 was of equal thickness, thus also tending to eliminate the possibility of lack of evenness and uniformity and providing a space between the flange 95 and a stuffing box flange 16 capping the base at the top of the air chamber 10 and resting upon the gasket 15 supported on the shoulder 14. This stuffing box flange has a stuffing box or cup 17 cast or formed integral therewith and extending down into the neck portion 11 of the air chamber or dome 10 and the bottom 18 thereof is centrally apertured to receive the pump or piston rod 19 and form an annular seat for a packing 20. The stuffing box 17 projects 100 above the plate or flange 16 as shown at 21 and is internally threaded to receive a stuff-

ing nut 22 serving to compress the packing and form a liquid and air-tight seal around the piston rod.

An annular upstanding shoulder 23 is also provided on the flange 16 in spaced relation to the upwardly projecting portion 21 and serves as a shoulder or guide to properly locate the bottom flanges or base fastening pad portions 24 of a cap or bracket 25 upon the top of the base 8 and on the plate 16. This cap is formed in two cast parts having the base flanges 24 of semi-annular form which abut at their meeting edges 26 and are bolted through the plate portion of the flange 16 and the flange 12, at suitably spaced points, as indicated at 27. Apertures are provided in these parts outwardly of the shoulder 14 for this purpose, so that the cap may be clamped to the base and the plate portion of the flange 16 maintained in liquid and air-tight connection therewith in conjunction with the gasket 15.

The cap or bracket 25 comprises two sections including sides or arms 28 having openings 29 to permit access to the nuts of the rear bolts 27 and said sides are in the form of upwardly extending arms and rearwardly extending arms 30. The upper ends of the sides or arms 28 are apertured to receive a bolt 31 for clamping the two sections together at the top, at which point the arms are provided with horizontal forwardly extending semi-circular portions 32 abutting to form an annular support or ring in which a bushing 33 is held and supported by the flange 34. The coacting edges of the portions 32 forming the ring are provided with opposed pairs of recesses 35 to receive lugs 36 of the bushing 33, which upon being inserted in position beneath the ring 32 and turning the bushing, will be moved out of alignment with the recesses as shown in Fig. 5 of the drawings to retain the bushing from upward displacement. The bushing is adapted to slidably receive a slide bar 37 of rectangular cross-section corresponding to the cross-section of the opening in the bushing as also seen in Fig. 5 of the drawings, and is connected to the piston rod 19 through the medium of a coupling 38 so that the two will move together.

The horizontal arms 30 of the bracket are provided with chamfered horizontal grooves 39 on their faces as seen more particularly in Figs. 3 and 4 of the drawings and the walls of the arms adjacent the ends of the grooves are provided with aligned openings 40 adapted to receive a horizontal clamping bolt 41 therethrough, said bolt also extending through a spacing and bearing sleeve 42 arranged between an opposed pair of openings and contacting with the end walls 43 of the grooves 39 according to the adjustment of the bolt as will be more fully explained. A fulcrum 44 in the form of a

bar or link has a sleeve 45 at its lower end pivoted on the sleeve or bushing 42 and the sleeve is formed with a lug 46 projecting rearwardly. The upper end of the fulcrum 44 is forked as indicated at 47 to pivotally support a handle 48. For this purpose, the fork receives the handle at the lower edge of the latter intermediate its ends but near the inner end and the vertical web of the handle is provided with a plurality of spaced openings 49 to receive a pivot pin 50 which also extends through apertures in the fork of the fulcrum and is adapted to permit adjustment of the connection along the length of the handle together with the adjustment of the lower end of the fulcrum in the openings 40. The inner end of the handle is forked at 51 to straddle the slide bar 37 and a pin 52 extends through aligned openings in the fork and slide bar to pivotally connect the handle to the latter for actuating the piston rod and pump.

In the position of the parts as shown in Figs. 1 and 3 of the drawings, the pivot 41 of the fulcrum 44 is located in the outer or rearward openings 40 and the upper end of the fulcrum is connected to the handle through the opening 49 remote from the pivotal connection 52 of the handle with the pump rod at the slide bar 37, so that the operation of the handle 48 will impart a maximum stroke to the piston of the pump in view of the leverage thus produced and the fact that the inner arm of the handle or lever is set for the longest adjustment provided for. During the operation of the pump, the fulcrum 44 will swing or oscillate to and fro on the sleeve 42 as a pivot, this back and forth movement of the upper end of the fulcrum compensating for the movement of the pivotal connection of the lever with the pump rod at 52 in a straight line or path vertically as the piston rod and plunger are reciprocated. The movable or shiftable pivot of the operating handle relieves the stuffing box and bearings, as well as piston rod, slide bar, plunger and connected parts of excessive stresses under the working stresses and forces which would tend to cause undue wear or result in the parts getting out of alignment or working order, thereby lengthening the useful life of the pump and parts thereof.

If it is desired to shorten the stroke, the pivotal connection 50 between the fulcrum and the handle is adjusted to the inner apertures or openings 49, the innermost adjustment giving the minimum stroke owing to the shorter leverage or lever arm between the pivotal connection of the fulcrum with the handle and that of the handle with the slide bar or pump rod. In order to compensate for this adjustment of the fulcrum on the handle and to permit the use of the same fulcrum with the shorter stroke, the

adjustment of the fulcrum on the cap or bracket 25 is provided and it is only necessary to remove the bolt 41 from the outer or rear openings 40 and shift the sleeve 42 so that its bore will align with the inner or forward openings 40 and then reinser the bolt and apply the nut thereto, in order to adjust the position of the fulcrum. This is due to the fact that the sleeve 42 is held in the grooves 39 and will maintain the fulcrum in pivotal connection and support the parts including the handle when the bolt is withdrawn so that the sleeve may be shifted in the grooves without disconnecting the fulcrum therefrom or dismantling the cap or bracket 25 from the base of the pump. This adjustment may be quickly accomplished and permits the stroke of the piston to be adjusted so that the pump can be operated at its highest efficiency. In Figs. 2, 3 and 4 of the drawings, it will be noted that the two-part casting comprising the cap or bracket 25 is provided with suitable reinforcing ribs 53 at the outside to give strength and lightness, the sections or sides of the base of the cap being enlarged to conform to the attaching portions 24. Diametrically opposed inwardly extending webs 54 are provided at the inside of the sections extending to and partly overlying the shoulder 23 to give additional strength for withstanding working stresses.

It will be noted from Fig. 5 that the slide bar 37 is of flat stock bar metal and operates through an oblong opening in the bushing 33 when employed in connection with the piston rod 19 to which it is connected by the coupling 38 when the device is used as a compression or force pump. In this instance, the packing establishes a fluid and air-tight connection with the piston rod and the gasket 15 establishes a similar connection between the base at its shoulder 14 and the stuffing box flange or plate 16. However, when it is desired to use the device as a lift pump, certain of the parts are interchangeable as illustrated in Fig. 7 in the drawings. In this case, the stuffing box flange 16 is replaced by a guide plate 55 which is bolted through the flange 12 in the same manner as previously described, in connection with the base of the cap or bracket 25 at the portions 24. However, in lieu of the stuffing box or cup 17 and the packing employed in connection therewith, the guide plate or flange 55 is formed with a guide sleeve 56 elongated or of thickened dimension with respect to the thickness of the plate and with a rectangular opening corresponding in cross-section to the cross-section of the slide bar 57 employed in connection therewith. In other words, the slide bar is sufficiently long to replace the piston rod 19 and operate through the long guide bearing or sleeve provided at the top of the pump base for connection with the plunger and operation thereof as a lift pump. In this event the pump base is made as a single casting with a cylindrical upper portion and the air chamber or dome 10 is omitted. The other parts of the structure are the same and in both cases the lug 46 on the lower end of the fulcrum serves as a stop with which the handle 48 contacts to limit the downward swing of the handle at the upper limit of the stroke of the piston and relieve the pivotal connection of the fulcrum 44 with the arms 30 of unnecessary shocks.

From the foregoing, it will be seen that I have provided a very desirable pump construction which may be interchangeably used as a compression or force pump and as a lift pump by replacing but few parts of the structure, according to the type of pump desired. The working parts are so constructed as to be of light weight and yet strong and durable and not likely to get out of working order. The operating parts are so made and connected that they may be readily assembled and the adjustment of the stroke of the pump may be easily accomplished to give the best possible operating efficiency. The bearings are so constructed that they may be readily replaced when worn. The two-part casting of which the cap of the pump is formed, together with the bracket arms thereof not only eliminates the necessity of coring as has been previously required in a cap of a single casting, but facilitates assembly, replacement and repair of the parts in addition to providing for more economical manufacture. The construction of the plate 16 with the integral stuffing box or cup 17 and the packing provided in connection therewith, considerably simplifies the construction and reduces the cost of production of the packing and bearing provided at this point for the piston rod, eliminating the necessity of employing a separate internally threaded bushing or sleeve in which threads extended entirely through the sleeve, thereby requiring a nut at the bottom in order to support the packing gland as heretofore employed. This also eliminates the use of a bottom nut or parts likely to get loose due to the constant jarring and vibration when the pump is working. While it is necessary to connect the two sections or parts of the cap and bracket, still the advantages accruing from the elimination of the coring and manufacturing difficulties met with in the making of a single part casting in the manufacture of the cap as heretofore done, greatly exceed the cost of connecting the parts or sections of a two-part construction irrespective of the advantages resulting from the additional facility of manufacture, assembling and replacement in accordance with the new construction. There are also the additional advantages of adjustment of

the stroke of the piston which especially requires a two-part cap or bracket structure for facility of assembling so that these features are reliant and more or less interdependent one upon the other. While I have described what I now consider to be the preferred embodiment of the invention, it is to be understood that the device is susceptible of wide changes and variations in the construction, arrangement and purposes of the parts as well as the materials used, without departing from the spirit and scope of the invention as will be hereinafter defined in the claims.

15 1. I claim:

1. In a pump of the class described, a base, a bracket mounted on the base, said bracket having opposed grooves, a fulcrum having a sleeve portion, a tubular bearing 20 for the sleeve portion having its ends seated in the grooves and slidably adjustable in the same, a bolt extending through the tubular bearing and adapted to hold the same in adjusted position in the grooves, a pump 25 rod, a handle pivotally connected to the pump rod, and a pivotal connection between the fulcrum and the handle.

2. In a pump of the class described, a base, a plate on the upper end of the base 30 and having a guide opening, a pump rod operating in said opening, a cap comprising a two-part member having coacting base portions jointly connected to the base with the plate, said cap portions having spaced 35 sides and coacting horizontal upper portions, a bushing held in the latter portions and slidably receiving the pump rod, connections between the sides of the cap, a handle pivotally connected to the pump rod 40 and extending between the sides of the cap, and a fulcrum supported for adjustment toward and away from the pump rod in the side portions of the cap and having adjustable connection with the handle.

45 3. In a pump, a base having a top flange formed with an upwardly projecting shoulder at the inside, a plate mounted on the shoulder, a gasket interposed between the plate and shoulder, said plate having an elongated sleeve portion for receiving a pump rod, and means to connect the plate and flange.

50 4. In a pump, a base having a top flange formed with an upwardly projecting shoulder at the inside, a plate mounted on the shoulder, a gasket interposed between the plate and shoulder, said plate having an elongated sleeve portion for receiving a pump rod, said sleeve having an apertured 55 end wall and forming a stuffing box, a packing in the box, a nut threaded in the sleeve over the packing, and a cap on the plate and bolted to the plate and flange.

55 5. In a pump of the class described, a base having a top shoulder, a plate mounted on

the shoulder and having an elongated sleeve portion at the center and an upstanding annular shoulder spaced therefrom, a bracket comprising separable sections having base portions engaging the shoulder to position 70 the bracket on the plate, means for connecting the plate and base portions to the base, a guide member supported in an outstanding position at the upper end of the bracket, a pump rod adapted to reciprocate in the 75 sleeve and member, connecting means between the sides of the bracket and positioned at the top and bottom thereof, a fulcrum pivoted between the sides of the bracket and a lever pivoted on the fulcrum 80 and having pivotal connection with the pump rod.

6. In a pump, a cap adapted to be arranged upon the top of a pump base, said cap comprising two sections having upwardly extending sides, connecting means between said sides, semi-circular portions formed with and projecting forwardly from the upper end of the sides and coacting to form a ring, said portions having coacting 90 recesses forming slots, and a pump rod receiving bushing having a top shoulder and peripheral projections adapted to enter the slots and disposed beneath the collar to retain the bushing from displacement. 95

7. In a pump, a cap in the form of a bracket comprising spaced side portions having semi-circular base portions abutting for engagement with the top plate of a pump base and adapted to be secured to the latter, said bracket having inner and outer reinforcing webs and openings for access to the attaching means thereof. 100

8. In a pump, a base having a top plate, a top bracket fitting on the top plate and adapted to be secured to the latter, arms projecting horizontally from the bracket and having internal grooves and communicating apertures disposed in opposed relation, a spacing and bearing sleeve disposed between the arms and having its ends movable in the grooves, a bolt to pass through said sleeve and selectively through any pair of opposed openings in said arms a fulcrum pivoted on the sleeve, a pump rod, and a handle connected therewith and with the fulcrum. 110

9. In a pump of the class described, a base having a top flange, a plate overlying the same having a guide opening for a pump rod, a cap in the form of a bracket having a base portion mounted on the plate, the plate and base portion being bolted together to the top flange of the base, a pump rod slidable in the plate and bracket, a fulcrum mounted on said bracket, and a pump handle connected therewith and with said rod. 120

10. In a pump, a base having a top flange formed with an upwardly projecting shoulder at the inside, a plate mounted on the

shoulder, a gasket interposed between the plate and shoulder, said plate having an elongated sleeve portion for receiving a pump rod, said sleeve having an apertured end wall and forming a stuffing box, a packing in the box, and a nut threaded in the sleeve over the packing.

11. In a pump, a cap adapted to be arranged upon the top of a pump base, said cap comprising two sections having upwardly extending sides, connecting means between said sides, semi-circular portions formed with and projecting forwardly from the upper ends of the sides and coacting to form a ring, said portions having slots, and a pump rod receiving bushing supported in the collar and having projections to pass into the slots and retain the bushing against displacement.

12. In a pump, a bracket having coacting recessed portions, a bearing bushing supported in the recesses, said portions having vertical slots in their inner faces and lugs on the bushing adapted to pass through the slots and engage the bottom of said portions to retain the bushing in position.

13. In a device of the class described, a top bracket to fit on the base of a pump, a packing member to fit between the bracket and base including a plate having a sleeve provided with an opening for receiving a pump rod, and an upstanding shoulder to provide means for locating said bracket in proper relation to said base.

14. In a device of the class described, a top bracket to fit on the base of a pump, said bracket having a fastening pad portion, a packing member to fit between the bracket and base including a plate having a sleeve provided with an opening for receiving a pump rod, and an upstanding annular shoulder for locating the pad portion of said bracket in proper relation to said base.

15. The combination with a pump base

having an outstanding flange at its upper end and an upstanding shoulder spaced from the outer edge of the flange; of a plate, a gasket between the plate and shoulder, said plate having a sleeve portion projecting above and below the same, and a cap bracket fastening to said outstanding flange with said plate and gasket therebetween.

16. The combination with a pump base having an outstanding flange at its upper end and an upstanding shoulder spaced from the outer edge of the flange; of a plate, a gasket between the plate and shoulder, said plate having a stuffing box projecting above and below the same, the bottom of the stuffing box being apertured and having a surrounding annular seat, a packing in the box, a nut threaded in the upper extension of the stuffing box and engaging the packing, and an annular projection on the plate around the stuffing box adapted to be engaged by a pump cap.

17. In a pump, the combination of a pump base having an outstanding flange at its upper end, a plate overlying the top of said base and having a central guide opening therein to receive a pump rod, a pump rod extending through said opening and above the pump base for operation, a cap bracket having a fastening pad portion overlying said plate, said bracket also providing a guide for a part co-extensive with said pump rod, means for operating said pump rod, and through bolts passing through said outstanding flange, through said plate and through the fastening pad portion of said cap bracket for holding said parts together in a rigid assembly.

18. In a pump as set forth in claim 17, the provision of a gasket between said plate and the top of said pump base to be compressed in the fastening together of said flange, plate, and cap bracket.

SWAN LARSON.
